UNITED STATES PATENT OFFICE.

ISRAEL R. TAYLOR, OF ASBURY PARK, NEW JERSEY.

PUZZLE.

SPECIFICATION forming part of Letters Patent No. 741,287, dated October 13, 1903.

Application filed August 7, 1903. Serial No. 168,659. (No model.)

To all whom it may concern:

Be it known that I, ISRAEL R. TAYLOR, a citizen of the United States, residing at Asbury Park, in the county of Monmouth and State of New Jersey, have invented certain new and useful Improvements in Puzzles, of which the following is a specification.

This invention relates to the type of household puzzles embodying game-pieces adapted to be moved upon a surface chiefly by hand to attain a predetermined position.

The purpose of this invention is to maintain the interest to the end, to train the eye, to develop the judgment, and to enable spare moments to be pleasantly spent in solitaire.

The essential feature of the invention is the provision of game-pieces of different shape, some being circular to represent balls and others being oblong to indicate rackets, the object being to get the pieces in a determinate position by manipulation of them by hand upon the base or tray.

In the drawings, Figure 1 is a top plan view of the puzzle embodying the invention, showing one position of the game-pieces. Fig. 2 is a view similar to Fig. 1, showing a different arrangement of the game-pieces. Fig. 3 is a section on the line X X of Fig. 2 with the cover in place. Fig. 4 is a perspective 30 view of the circular or disk game-piece. Fig. 5 is a perspective view of the oblong or racket-shaped game-piece.

Corresponding and like parts are referred to in the following description and indicated in all the views of the drawings by the same reference characters.

The base 1 is preferably of square form and is provided in one side with a circular depression 2. When the base consists of a block of wood, the recess 2 is bored therein or formed by removing a portion of the material. In the event of forming the base of sheet material—such as metal, paper, or the like—the recess 2 may be formed by pressing a portion of the material from the blank, as will be readily comprehended. The depression 2 may be of any diameter and depth, according to the size of the game-pieces and the

number thereof. The open side of the depression is closed by a cover 3, which may be fitted to the base in any manner.

The game-pieces 4 and 5 are of different shapes, the elements 4 being circular or of disk form and the parts 5 of oblong or racket outline. The game-pieces are approximately of like and uniform thickness, corresponding approximately to the depth of the recess or depression 2, so as not to project above the plane of the upper side of the base, thereby admitting of the cover fitting snugly thereon. The game-pieces may be constructed of any material best adapted for the purpose and according to the finish and cost of the game device. The relative size of the game-pieces and depression is such as to admit of movement of the game-pieces so as to attain the desired end. The game-pieces may be arranged in the recess or depression 2 in any manner—such, for instance, as shown in Figs. 1 and 2—the purpose being to secure a definite relation of the game-pieces by moving them by hand until the desired arrangement is effected. As shown in Fig. 1, the game-pieces 4 alternate with the game-pieces 5, and the latter have a radial arrangement, the smaller ends, necks, or handles converging toward the center. When arranged in this way, the object in view is to assemble like pieces in groups, as shown most clearly in Fig. 2. On the other hand, should the game-pieces be arranged as in Fig. 2 at the outset the object to be attained is to secure an alternate position of the game-pieces about as shown in Fig. 1. Obviously any arbitrary arrangement of the game-pieces, either at the outset or at the finish, may be determined upon according to the required skill in attaining the ultimate result.

Having thus described the invention, what is claimed as new is—

1. A puzzle comprising a base having a recess forming a playing-field, and two sets of game-pieces, one set being of circular outline and the other set of oblong form and provided at one end with narrow or necked portions to admit of grouping the oblong game-

pieces about a central point with the circular game-pieces alternating, substantially as specified.

2. The herein-described puzzle comprising
5 a base having a circular recess in one side forming a playing-field, two sets of game-pieces of a thickness corresponding approximately to the depth of the recess, one set of game-pieces being of circular outline and the

other set of oblong form, substantially as set forth.

In testimony whereof I affix my signature in presence of two witnesses.

ISRAEL R. TAYLOR. [L. S.]
